UNITED STATES PATENT OFFICE

GUSTAV TAUSCHEK, OF VIENNA, AUSTRIA, ASSIGNOR TO THE TABULATING MACHINE COMPANY, OF ENDICOTT, NEW YORK, A CORPORATION OF NEW JERSEY

TABULATING, CALCULATING, AND SIMILAR MACHINE

Application filed May 28, 1930, Serial No. 456,367, and in Austria July 25, 1927.

This application is a continuation in part of my earlier application Serial No. 295,264, filed July 25, 1928.

My invention relates to tabulating, calculating and similar machines and has for one of its objects to provide mechanism for use in such machines for printing text and the like relating to the results obtained by interpreting perforated cards or by performing a 19 calculation simultaneously with such interpretation or calculation.

The practical value of my improved mechanism will become evident when it is considered that in most cases the holes represented in perforated cards also represent codes for names, places, materials and the like the meaning of which must be ascertained after the particulars are tabulated. So, for instance, in a list of wages, made according to a usual method by means of perforated cards, the number of the respective workman appears, not however, his name which, for control purposes, must be ascertained when the wages are actually paid.

25 It is an object of the present invention to provide a mechanism whereby, during the tabulating of, for example, wage cards, there is simultaneously automatically selected a type slug belonging to such card and located 30 in a magazine, and printed opposite the tabulated particulars of the card.

In the accompanying drawing is shown by way of example a perspective view of an embodiment of the invention.

35 At the side wall 1 of a tabulating machine a type slug magazine 2 is fixed in such a manner, that its upper portion cooperates with an extended platen 3 of the tabulating machine. The type slug magazine 2 comprises two compartments 4 and 5 containing the matrices 17 to be printed and those already printed from, respectively.

40 In accordance with the present invention, the type slugs, after the printing therefrom, are automatically transferred from the compartment 4 to the compartment 5, while at the same time other type slugs are transferred from compartment 5 to compartment 4 in regular sequence. This transfer is accomplished with the aid of a reciprocating

mechanism comprising levers 6 and 15 pivotally mounted intermediate their ends at 7 and 8 respectively upon fixed parts of the machine, the pivot 7 being upon a lug 9 extending from one of the magazine walls. The levers 6 and 15 are connected by a link 10 to move in unison. The lever 15 carries at its upper end a slide 16 which enters a slot in the side wall of the magazine, and is so positioned and reciprocated in such manner by mechanism presently to be described, that it engages the uppermost type slug in compartment 4 and pushes the same before it on top of uppermost slug in the type slug compartment 5. The lever 6 is similarly provided at its lower end with a slide 16' which, simultaneously with the operation of the slide 16, enters the compartment 5 through a slot in the left wall of the magazine and pushes the lowermost matrix in compartment 5 to 70 the compartment 4. As shown in the drawing the edges of the type slugs are beveled, so that when a type slug is forced into the compartment 4, it will lift the stack of type slugs 17 in the latter. 75

The levers 6 and 15 are oscillated to produce reciprocation of the slides 16 and 16' by means of disc 11 having a cam groove thereon which is engaged by the lower end of the lever 15. The disc 11 is mounted on 80 a shaft 19 which is operatively connected to the drive shaft of the tabulating machine.

Also mounted on the shaft 19 is a cam disc 12 which is engaged by a lever 13' and is so formed that it operates to shift at each revolution a hammer 13 and thereafter releases it for a printing movement by the action of a suitable spring. The disc 12, instead of being cam-shaped, may be provided with a pin projecting laterally therefrom which engages the lower end of lever 13' and swings the same at each revolution, the hammer being thereby moved away from the platen and; upon release of the lever by the pin, the hammer is caused to strike the type slug positioned in the path of the hammer. 90

The operation of the hammer 13 and of the slides 16 and 16' is accomplished in properly timed relation by means of couplings 20 and 21, respectively, which connect the 100

discs 12 and 11 to the shaft 19. The couplings are rendered effective by the armatures of magnets 22 and 23 when the circuits of the latter are closed by mechanism immediately to be described.

The circuit of the two coupling magnets 22 and 23 are opened and closed by the two feelers 24 and 25. These feelers are disposed adjacent to the feelers 26 which serve to control the computing or typing mechanism of the tabulating machine. The feeler 24 is in contact either with the supporting plate 27 or with the card to be sensed; while the feelers 25 and 26 are pressed by means fully shown in the patent to Tauschek 1,617,088 toward the supporting plate only when a card is positioned on the latter, and at other times are raised above such plate. The computing and typing mechanism may be constructed as shown in United States Patent #1,617,088. The feeler 24 is so arranged that it engages the imperforated margin of the card, while the feeler 25 may engage a special row of perforations reserved therefor in the card. By this arrangement the feeler 24 will excite the magnet 22 after every card and thereby throw in the coupling 21, whereby a shifting of the type slug is produced. Printing of an item from the type slug will, however, take place only when a perforation in the card is engaged by the feeler 25. In such event, the magnet 23 is energized and throws in the coupling 20 which operates the hammer 13. If no perforation is present in the column engaged by the feeler 25, then no printing takes place. For illustrative purposes only the clutch devices are shown diagrammatically and in conventional form. The specific form may comprise those shown in either Hollerith Patent 677,214 or 685,608 in conjunction with the associated control devices disclosed in these patents whereby the momentary energization of the clutch control magnets will be continued by separate means in order to effect a complete revolution of the operating cams and thereafter render them ineffective. In order to insure that the discs 11 and 12 make a complete revolution even when the magnets 22 and 23 are excited for only a very short time, there are provided noses 28 and 29 each of which, as soon as a magnet attracts its armature and thereby throws in the associated coupling, holds the latter in such position for whole revolution.

As the adjustable coupling 20 is controlled by the feeler 25, and as such feeler must engage perforations in the card being sensed before the circuit of the associated magnet 23 can be closed, the mechanism can be so controlled that a type slug is printed from only after a certain number of cards have been sensed and which precede special cards having perforations in alignment with brush

While I have shown the type slugs arranged in vertical columns, the invention is not limited to such an arrangement for the columns may extend obliquely or horizontally. Where, therefore, in the claims I employ the terms "top" and "bottom", the same are to be understood as defining the opposite ends of the type slug compartments and not as specifying a vertical arrangement for such compartments.

I claim:

1. In a tabulating machine, the combination of sensing mechanism for interpreting a perforated card, a magazine having two compartments arranged side by side for receiving type slugs in columnar relation, means for guiding a web of paper for receiving imprints thereon, a hammer arranged to engage one of said type slugs to cause the same to print on said web, a reciprocable slide arranged to transfer type slugs from the top of the first compartment to the top of the second, a second reciprocable slide arranged to transfer type slugs from the bottom of the second compartment to the bottom of the first, means controlled by said card for operating said hammer, and means for reciprocating said slides.

2. In a tabulating machine, the combination of sensing mechanism for interpreting a perforated card, a magazine having two compartments arranged side by side for receiving type slugs in columnar relation, means for guiding a web of paper for receiving imprints thereon, a hammer arranged to engage one of said type slugs to cause the same to print on said web, a reciprocable slide arranged to transfer type slugs from the top of the first compartment to the top of the second, a second reciprocable slide arranged to transfer type slugs from the bottom of the second compartment to the bottom of the first, means controlled by said card for operating said hammer, and means for reciprocating said slides.

3. In a tabulating machine the combination with a magazine having two compartments arranged side by side for receiving type slugs in columnar relation, of means for guiding a web of paper for receiving imprints thereon, a hammer arranged to engage one of said type slugs to cause the same to print on said web, means for transferring type slugs from the first compartment to the second and from the second to the first, means for operating said transferring means, a driven shaft, and electromagnetic means controllable by a card introduced in the machine for coupling the transferring means to said shaft.

4. In a tabulating machine the combination with a magazine having two compartments arranged side by side for receiving type slugs arranged in columns, means for guiding a web of paper for receiving im-

- prints thereon, a hammer arranged to engage one of said type slugs to cause the same to print on said web, a reciprocable slide arranged to transfer type slugs from the top 5 of the first compartment to the top of the second, a second reciprocable slide arranged to transfer type slugs from the bottom of the second compartment to the bottom of the first, a pair of linked levers for reciprocating 10 said slides, a cam for oscillating one of said levers, a driven shaft, a coupling between said cam and said shaft, and an electromagnet controllable by a card introduced in the machine for operating said coupling to connect 15 said cam to said shaft.
5. In a tabulating machine the combination with a magazine having two compartments arranged side by side for receiving type slugs arranged in columns, means for 20 guiding a web of paper for receiving imprints thereon, a hammer arranged to engage one of said type slugs to cause the same to print on said web, a reciprocable slide arranged to transfer type slugs from the top 25 of the first compartment to the top of the second, a second reciprocable slide arranged to transfer type slugs from the bottom of the second compartment to the bottom of the first, a lever for operating said hammer, a spring 30 urging the hammer to engage a type slug, a cam arranged to oscillate said lever against the action of said spring, a driven shaft, a coupling between said coupling and said shaft, and an electromagnet controllable by a 35 card introduced in the machine for operating said coupling to connect said cam to said shaft.
6. In a tabulating machine the combination with a magazine having two compartments 40 arranged side by side for receiving type slugs arranged in columns, means for guiding a web of paper for receiving imprints thereon, a hammer arranged to engage one of said type slugs to cause the same to print on said 45 web, a reciprocable slide arranged to transfer type slugs from the top of the first compartment to the top of the second, a second reciprocable slide arranged to transfer type 50 slugs from the bottom of the second compartment to the bottom of the first, means for operating said hammer, and an electromagnet controllable by a card introduced in the machine for controlling the operation of said 55 hammer operating means.
7. In a machine of the class described the combination with a platen, of a series of printing members in a compartment, means adapted to successively transfer said printing members to be correlated with the part of the sheet 60 which is to be imprinted and which is carried by said platen for a printing operation, means for shifting a printing member to coact with said sheet, and means under control of a tabulating card introducing in the machine to 65 effect the automatic operation of the shifting means.
8. In a machine of the class described, printing members successively transferable to a platen and adapted to print legends identifying data derived from tabulating cards, means operated at selected operations of the machine for shifting a printing member to effect a printing operation, and means controlled by specially designated tabulating cards for causing automatic operation of the last mentioned means. 70
9. In a machine of the class described, the combination with printing members transferred in a fixed sequence for identifying data derived from tabulating cards, of means for shifting a printing member to effect a printing operation, and means operable during selected machine operations determined by the analyzing of special designated tabulating cards for causing automatic operation of the last named means. 75
10. In a tabulating machine, the combination with printing members for identifying data derived from tabulating cards, of means controlled by the separation of a card from a special controlling element for causing a printing member to be shifted for a printing operation, and means whereby special designations of a tabulating card causes a printing operation from the shifted printing member. 80
11. In a tabulating machine the combination with identifying printing members, of means operable between successively fed tabulating cards for effecting the presentation of a printing member to identify data derived from a following specially designated tabulating card, and means whereby the special designation of said card effects a printing operation from the last printing member presented. 85
12. In a tabulating machine, the combination with identifying printing members, of means operable as an incident to each tabulating operation for shifting a printing member for a printing operation, means for feeding individual tabulating cards of a series, and means operable during selected tabulating machine operations represented by the simultaneous feeding of and control by a special tabulating card in the series for effecting a printing impression from a shifted printing member. 90
13. In a tabulating machine, the combination with a series of identifying printing members, of means for presenting said members in sequence for printing operations, means for feeding individual tabulating cards of a series, and means under control of a tabulating card having a special designation for effecting a printing operation from a printing member presented in the same machine operation. 110
14. In a tabulating machine, the combination with an analyzing device for analyzing 120
- 125
- 130

ing successively fed individual tabulating cards, of printing members shifted as an incident to the analyzing of each individual tabulating card, and means controlled by 5 only one special designation of an individual card when analyzed by a part of said analyzing device for causing a printing operation from a printing member, the other part of said analyzing device controlling the 10 printing of other data supplemental to the data printed by the printing member.

15. In a tabulating machine the combination with identifying printing members, of means for successively transferring printing members for printing operations, means for analyzing individual perforated records, and means operable during an analyzing operation from an individual record for effecting a printing operation from a printing member 20 to identify data derived from the individual tabulating record analyzed.

16. The invention according to claim 15 with the provision of means for effecting printing operations only when the individual 25 record has a special perforation.

17. The invention according to claim 15 with the provision of means whereby a printing member is presented for each individual tabulating record analyzed and the printing 30 means is only effective for printing when the individual tabulating record has a special designation.

18. The combination with a record con-

trolled tabulating machine including a driving mechanism therefor, of a printing mechanism comprising conveying means adapted to bring printing members separately into printing position opposite the surface to be 70 printed, means effective for each tabulating machine operation for operating said conveying means to present individual printing members to the printing surface and a clutch mechanism adapted to selectively connect said operating means to the driving mechanism of the tabulating machine, said clutch mechanism being controlled by the record cards 75 which control the tabulating machine.

19. The combination with a tabulating machine including a driving mechanism therefor, of a printing device comprising conveying means adapted to bring printing members separately into printing position opposite a surface to be printed, means effective 80 for each tabulating machine operation for operating the conveying means to present individual printing members to the printing surface, means for effecting printing from said printing members and a clutch adapted 85 selectively to connect the printing means with the driving mechanism of the tabulating machine, said clutch being controlled by the record cards which control the tabulating machine. 90

In testimony whereof I have hereunto set my hand.

GUSTAV TAUSCHEK.
